D8-305.

OR, D12,378

EX

UNITED STATES PATENT OFFICE.

RODOLPHE CHRISTESEN, OF NEW BRITAIN, CONNECTICUT, ASSIGNOR TO
THE RUSSELL & ERWIN MANUFACTURING COMPANY, OF SAME PLACE.

DESIGN FOR A BELL LEVER AND PLATE.

SPECIFICATION forming part of Design No. 12,378, dated August 2, 1881.

Application filed May 25, 1881. Term of patent 7 years.

To all whom it may concern:

Be it known that I, RODOLPHE CHRISTESEN, a citizen of the United States, residing at New Britain, in the county of Hartford and State of Connecticut, have invented and produced a new and original Design for a Bell Lever and its Plate, of which the following is a specification, reference being had to the accompanying engraving, forming part thereof, 10 which represents the same in perspective.

The contour of the plate A is composed of straight and curved lines in the form clearly shown. A plain raised border extends around the edge. The lower end contains a five-sided panel, two of which sides form a point at the middle of the bottom, and said panel is ornamented by a rosette, leaflets, and berries, as shown. Above this panel so much of the middle of the plate as is not occupied by the bell-lever B is ornamented by curved and straight raised bars, rosettes, and leaflets. Toward the upper end, and just above the lever, the raised bars intersect each other and form squares upon either side, and between the surfaces so ornamented there is the representation of a vase, a, from which rises the representation of a flowering plant, and over one of the flowers is the representation of a hovering butterfly. The lever B extends vertically for a short distance, then it projects obliquely upward away from the plate and is surmounted by a cross-piece, b, which forms the handle. The front of the vertical portion of the lever is ornamented by a raised border, a rosette, and a branching ornament. The front of the oblique portion is ornamented by four simple grooves disposed as shown, and the front of the cross-

piece or handle b is ornamented by a central panel containing the word "Pull" in ornamental letters, a plain raised ledge above and below said word, two vertical bars at each side thereof, and pointed ornaments outside of said bars. Each end of the handle is of pyramidal form, and a bead, c, forms the junction of said ends and body of the handle. 40 45

I claim—

1. The design for the bell lever and plate herein shown and described, the same consisting of the plate, the lower panel of which is five-sided, and ornamented by the rosette and leaflets. 50

2. The design for the bell lever and plate herein shown and described, the same consisting of the plate, the upper end of which is ornamented by the border, intersecting raised bars, the vase, flowering plant and butterfly. 55

3. The design for the bell lever and plate herein shown and described, the same consisting of the plate, the front of which is ornamented by the curved and straight bars, the several rosettes, leaflets, vase, flowering plant and butterfly. 60

4. The design for the bell lever and plate herein shown and described, the same consisting of the lever B and its handle b, having pyramidal-shaped ends, the bead c and pointed ornaments, the grooves on the front of the oblique portion and the border, rosette, and branching ornament on the face of the vertical portion. 65

RODOLPHE CHRISTESEN.
